UNITED STATES PATENT OFFICE.

WILLIAM S. BARKER, OF DAYTON, OHIO.

COMBINATION CONCRETE BLOCK AND BRICK MACHINE.

No. 839,092.

Specification of Letters Patent.

Patented Dec. 25, 1906.

Application filed June 8, 1906. Serial No. 320,775.

To all whom it may concern:

Be it known that I, WILLIAM S. BARKER, a citizen of the United States, residing at Dayton, in the county of Montgomery and State 5 of Ohio, have invented certain new and useful Improvements in Combination Concrete Block and Brick Machines; and I do declare the following to be a full, clear, and exact description of the invention, such as will enable 10 others skilled in the art to which it appertains to make and use the same, reference being had to the accompanying drawings, and to the figures of reference marked thereon, which form a part of this specification.

15 This invention relates to new and useful improvements in concrete building-block and brick machines.

The object of the invention is to provide a machine of the above character which has 20 capacity for expeditiously molding concrete building-blocks or concrete bricks of standard size.

A further object of the invention is to provide a machine of the above type which has 25 a capacity for forming different thicknesses of blocks with facility and to provide such blocks with different faces, or, in other words, different surface designs.

A further object of the invention is to provide a machine which is easily manipulated in both forming and delivering the block and which avoids endangering the block in any manner in delivering the same, all as will hereinafter more fully appear.

35 In the drawings, Figure 1 is a top plan view showing the mold open. Fig. 2 is a front elevation showing the mold open. Fig. 3 is a side elevation with the lower framework omitted. Fig. 4 is a cross-section of 40 the mold-box closed. Fig. 5 is a detail perspective view of the partition-plates utilized for making bricks of standard size. Fig. 6 is a detail perspective view of the face-plate used in connection with Fig. 5 in making 45 bricks. Fig. 7 is a detail perspective view of the tamping-plate utilized when making bricks. Fig. 8 is a cross-sectional view of the mold, showing the same equipped for making standard-size concrete bricks.

50 In a detail description of the invention similar reference characters indicate corresponding parts.

I will first describe the apparatus in its equipment for making concrete blocks.

55 1 and 2 designate the lower and upper framework, the lower framework consisting

of standards which are joined at their upper ends in a solid portion 1^a, which supports the upright rear side 3 and ends 4 of the mold. These rearward and end walls 3 and 4 are 60 rigidly united by being bolted together and to the upper solid portion 1^a of the framework, forming a support for the mold. These rearward and end walls 3 and 4 are therefore at all times stationary, and this is an im- 65 portant feature in that it enables the completed blocks to be removed from the mold without endangering the same.

7 is the face-plate, which forms the bottom of the mold in the formation of the concrete 70 block. This face-plate is rigidly secured to a suitable number of brackets 8—for example, two of such brackets—and these brackets are rigidly secured to the front side plate 9, which is hinged at 10 to the end plates and 75 will be again referred to. As the face-plate 7 is shown in Fig. 4 it is designed to produce a rock-face to the block when finished; but it will be understood that such bottom plate may be provided with any surface that it is 80 desired to impress upon the face of the block, either smooth surface or any ornamental surface. The thickness of the block may be decreased to from two to four inches by elevating the bottom of the mold or the face-block 85 7 within the mold, thus decreasing the depth of said mold. This is accomplished by moving the supporting-brackets 8 to a higher position and uniting them to the front side wall 9 by passing the securing-bolts 11 90 through the openings 12 in said front side wall. These blocks of less thickness are used merely as facing or veneer blocks in some instances and do not take the place of the main blocks of the building. 95

It will be understood that the face of the block is not changed whether the block is reduced in thickness by elevating the bottom of face-plate 7 or whether said face-plate is in a position to form a building-block of maximum thickness.

Owing to the brackets 8 being attached to the front side plate 9 and the bottom or face plate 7 being attached to the said brackets, it will be seen that when the mold is open, as 105 in Fig. 3, the finished block is delivered with its outer side down upon the pallet 13. The bottom or face plate 7 at this time lies in the rear in a vertical position, and the block is removed away from the face-plate without 110 endangering the face formation thereof.

14 represents end plates, which are hinged

at 15 to the front side plate 9 and are adapted to fit in the mold against the ends 4 when the front side plate 9 is elevated to a vertical position, as in Fig. 4. When said front side plate 9 is opened upon the pivots or hinges 10, these end plates 14 are swung outwardly, as shown in Fig. 1, to clear the ends of the block and permit said block to be removed upon the pallet 13. The pallet 13 has secured to it cleats 16, which rest upon the front side plate 9 and afford suitable space below said pallet for the hands to secure a hold upon the pallet in removing the same with the finished block. The pallet 13 incloses the outer edge of the bottom of the mold or the face-plate 7, while the rearward wall 3 of the mold incloses the rearward edge of said face-plate. The hinged end plates 14 have cores 18 secured thereto, which form a semicircular vertical groove in the ends of the block. One of these end plates 14 is shown without a core 18. This is the case when one end of the block is exposed at the corner of the wall built up by these blocks. In the case of all of the blocks whose ends are inclosed by the abutting ends of the adjacent blocks two such cores 18 are used to provide the necessary space for the application of cement in building a wall. The outer edges of the stationary end walls 4 are rounded, as at 4'. These rounded edges act as cams to throw inwardly the hinged end plates 14 when the front side wall 9 is being elevated upon its pivots 10 to close the mold preparatory to the formation of a block. The front side wall 9 is provided with two locking-notches 9', which receive keys 19, serving to lock said front wall in its upright position. These keys 19 are pivoted to the outer sides of the end walls 4 at 20, and on the outer ends of said keys there are pivoted at 21 handles 22, by means of which the keys 19 are swung into the notches 9'. At the pivots 21 there are eccentrics 23, which engage the outer side of the plate 9 when the handle portions 22 are moved parallel with the plate 9, or nearly so. These eccentrics 22 thus serve to hold the front side plate 9 rigidly in its upright position.

50 The upper surface of the block within the mold is tamped by a tamping-plate 24, carried upon arms 25, pivoted at 26 to brackets 27, rigidly attached to the rear wall 3 of the mold. Joining the upper ends of the arms 25 is a handle 28, which is grasped by the hand in lowering the tamping-plate 24 to tamp the concrete within the mold in the formation of the block.

29 represents two resilient arms, which are rigidly united at the lower ends to the rear wall 3 of the mold and have a suitable seat 30 to receive the journals of the handle 28 to support the tamping-plate in an elevated position when out of use. In elevating the 55 tamping-plate to this position the seat 30

readily enters below the journals of the handle, owing to the resilient nature of the arms 29.

In order to relieve the brackets 8 of undue strain at a point farthest from their points of attachment with the front side plate 9, I provide means for engaging the rearward portion of the bottom or face plate 7. This means consists of an adjustable member 31, which is slotted to receive a screw 32. This screw engages a stationary projection 33, extending from the rear wall 3 of the mold, and by this means the member 31 is secured in position with its upper end abutting against the lower side of said face-plate 7 at the extreme rearward edge of said face-plate.

I have thus far described my improved concrete-block machine when utilized for molding concrete blocks of various sizes, and it will be understood that the inner surfaces of the end plates 14 may be provided with 85 rock-face surfaces or any other surface that it is desired shall be impressed upon the ends of the block. It may be also stated in connection with these end plates 14 that the cores 18 are detachable and may be united 90 to said end plates in the center of said plates or on either side of a center line, and thus the recesses in the ends of the blocks may be placed at desirable points.

Through the instrumentality of the parts 95 illustrated on sheet 4 of the drawings the machine is transformed into a machine for making in one operation a series of bricks of standard size. For this purpose the depth of the mold is decreased by placing therein a 100 series of base-plates 5, which are in the form of brackets with upper smooth surfaces and intervening spaces 6. The base plates or brackets 5 are rigidly attached to an inner plate 17 by means of bolts 34, said inner 105 plate 17 being bolted through openings 35 to the upper portion of the front plate 9. It will thus be seen that the plates or brackets 5 are rigidly united to the supplemental plate 17, which in the present instance takes the 110 place of the pallet-board 13, and said plate 17 is rigidly united to the hinged plate 9, so that the plates or brackets 5, upon which the bricks are supported, are moved upwardly and outwardly to deliver the bricks.

36 is a rearward interior plate which supports a series of division-plates 37, which enter the spaces 6 between the bottom plates or brackets 5, and thus separate the mold into a series of uniform individual molds. This 115 rearward plate 36 is rigidly secured to the rearward wall 3 of the mold by a suitable number of bolts 38, so that said plate 36 and the division-plates 37 are held stationary when the bottom plates or brackets 5 are being moved upwardly and outwardly between said division-plates. The front side plate 9 is constructed of two parts, which are united 125 on the line 39 by hinges 40. When the machine is used for molding a series of bricks, 130

the upper hinged section of said front side plate 9 is lowered upon the hinges 40 to deliver the brick. The lower section of said wall 9 is united to the end walls 4 of the mold by a suitable number of screws 41, which penetrate openings 41 and secure said lower portion of said wall 9 rigidly to the end walls of the mold. The inner supplemental wall 17, as before stated, is secured by screws entering openings 35. These screws penetrate openings 35 in the upper hinged portion of the front side wall 9, and said wall 17 essentially has no connection with the lower stationary portion of said wall or plate 9.

15 When the mold is used for forming blocks, the two portions of the front side wall 9 are made rigid at the hinged joint 39 by cleats 42, which are rigidly attached to said parts and cross the hinged joint, so that the front 20 side wall 9 becomes one rigid part, which is opened outwardly upon the pivots 10.

25 43 is an operating-rod which is utilized to elevate the front side wall 9 and to afford a support, as shown in Fig. 2, when said front side plate 9 is lowered to a horizontal position to remove the molded block, which is supported thereon by the pallet-board 13. This supporting rod or handle 43 is attached to the upper portion of the front side plate 9, so 30 and thus becomes a support for the upper portion of said plate when the apparatus is used to mold bricks. In this case it will be understood that the upper portion of the front side wall 9 is opened upon the hinges 40, so 35 that in either event the supporting rod or handle 43 acts as a standard to support the front side plate 9 or the upper hinged section of said plate in delivering the molded blocks or bricks.

40 In the manufacture of bricks the tamping-plate 44 (shown in Fig. 7) is substituted for the tamping-plate 24 by being attached to the pivotal arms 25. This brick-tamping plate 44, it will be observed, has a series of 45 grooves 45 in its tamping-face which receive the upper edges of the division-plates 37 in the tamping operations.

27^a designates guides secured to the arms or brackets 27 and serving to center or guide 50 the tamping-plate 24 when the latter is lowered in the operations of tamping.

55 In delivering the series of bricks supported upon the plates 5 the said plates are moved upwardly and outwardly in a half-circle with the faces of the brick upward, said bricks being delivered in such position upon a pallet. The faces of the bricks may be given any ornamentation or color desired.

A two-piece wall-block may be made in the 60 machine by placing a suitably-shaped pallet in place of the face-plate 7. The pallet in this case may be made to core out any desired shape on the inside of the block.

I claim—

65 1. In a concrete-block machine, the com-

bination with two rigid end walls and a rigid side wall forming the mold-box, of a front wall having a pivotal connection at its base to open outwardly, and two inside end plates hinged at their lower ends to the front wall or 70 plate and adapted to be removed from the mold in opening said front plate.

2. In a concrete-block machine, the combination with three rigid plates forming the rear side wall and the two end walls of the 75 mold, of a front plate forming the front side wall of the mold, said front plate being pivoted at its base to open outwardly, and two inside end plates hinged at their lower ends to the front plate and adapted to open out- 80 wardly on said hinges when the front plate is lowered upon its pivot.

3. In a concrete-block machine, the combination with three rigid plates forming the rear side wall and the two end walls of the 85 mold, of a front plate forming the front side wall of the mold, said front plate being pivoted at its base to open outwardly, two inside end plates hinged to the front plate and adapted to be opened outwardly when the 90 front plate is lowered, and a face-plate forming the bottom of the mold and supported upon the front side wall.

4. In a combination concrete block and 95 brick machine, a mold having three rigid plates forming the rear side wall and the two end walls of the mold, a front plate forming the front side wall of the mold, said front plate being pivoted at its lower edge to open outwardly from the mold and having an upper hinged section and a series of plates forming the bottom of the mold rigidly attached to the upper hinged portion of the 100 front side plate of the mold.

5. In a combination concrete block and 105 brick machine, a mold having three rigid plates forming the rear side wall and the two end walls of the mold, a front plate constructed of two parts having a hinged connection and the lower part being pivotally connected 110 at the base of the mold, means for rigidly uniting the two hinged portions of said front plate, brackets extending rigidly from the lower inner side of said front plate and forming the bottom of the mold, and end plates 115 pivoted to the lower portion of the front side plate and lying against the stationary end walls of the mold when the front plate is elevated, and means for tamping the material within the mold. 120

6. In a combination concrete block and 125 brick machine, a mold having three rigid plates forming the rear side wall and the two end walls of the mold, a front plate pivoted to the base of the mold and forming the front side wall of the mold, a face-plate rigidly attached to the front side plate of the mold and forming the bottom of the mold, and means for independently supporting the rearward edge of said face-plate when forming the bot- 130

tom of the mold and to relieve the supports for said face-plate from undue strain in the operation of tamping the material.

7. In a combination concrete block and brick machine, a mold having three rigid plates forming the rear side wall and the two end walls of the mold, a front plate having a pivotal connection with the base of the mold and forming the front side wall thereof, a face-plate supported upon said front plate and forming the bottom of the mold, and a standard attached to said front plate and forming the handle to operate said plate and the standard to support said plate when lowered.

8. In a combination concrete block and brick machine, a mold having three rigid plates forming the rear side wall and the two end walls of the mold, a front plate consisting of two hinged portions, the lower hinged portion being rigidly attachable to the end plates of the mold, the upper portion of said front plate opening outwardly upon its hinges, a series of brackets rigidly attached to said upper hinged portion and forming the bottom of the mold, a series of division-plates fitting between said brackets and providing a series of mold-spaces, said division-plates being rigidly attached to the rear wall of the mold and

permitting of the passage of the bottom 30 plates or brackets in delivering the brick from the mold.

9. In a combination concrete block and brick machine, a mold having three rigid plates forming the rear side wall and the two 35 end walls of the mold, a front plate consisting of two hinged portions, the lower portion of said plate being rigidly attached to the end plates of the mold, and the upper portion of said front plate being hinged to open outwardly, means for securing said hinged portion in an upright position, a series of bottom plates rigidly attached to an inner plate, said inner plate being rigidly attached to the upper hinged portion of the front plate of the 45 mold, a series of division-plates rigidly connected to a side plate, said side plate being rigidly attached to the rear wall of the mold, the series of division-plates intersecting the bottom plates and dividing the interior of the 50 mold into a plurality of uniform mold-chambers.

In testimony whereof I affix my signature in presence of two witnesses.

WILLIAM S. BARKER.
